(57) CLAIM

The ornamental design for a jar, as shown and described.

DESCRIPTION

FIG. 1 is a front elevation view of a jar showing my new design;

FIG. 2 is a right side elevation view thereof;

FIG. 3 is a top plan view thereof;

FIG. 4 is a rear elevation view thereof; and,

FIG. 5 is a left side elevation view thereof.

The broken lines shown in the drawings represent unclaimed environment and are for illustrative purposes only, forming no part of the claimed design.
